UNITED STATES PATENT OFFICE.

HENRY BERG, OF ORANGE, NEW JERSEY.

SOLDERING-IRON.

No. 850,897.

Specification of Letters Patent.

Patented April 23, 1907.

Application filed March 2, 1906. Serial No. 303,752.

To all whom it may concern:

Be it known that I, HENRY BERG, a citizen of the United States, residing in the city of Orange, county of Essex, and State of New Jersey, have invented a new and useful Improvement in Soldering-Irons, of which the following is a full, clear, and exact description, such as will enable others skilled in the art to which it appertains to make and use the same.

The object of my invention is to construct a soldering-iron of the gasolene type, in which a constant fuel-feed is provided with which to heat the bit and also to provide supplemental means for regulating the combustion and consequent consumption of fuel. In soldering-irons of this type much difficulty is experienced in maintaining a constant flow of fuel to the burner and a uniform and very intense heat within the bit or head of the "iron." I have effectually overcome these and other difficulties as well as simplified the construction by the means hereinafter described, and illustrated in the accompanying drawings, in which—

Figure 1 is a longitudinal sectional view of my improved construction. Fig. 2 is an end view of the front cap with the forward parts removed. Fig. 3 is a sectional view through the reservoir looking toward the front cap. Fig. 4 is a view of one form of air-regulator. Fig. 5 is a plan view of the usual soldering-bit. Fig. 6 is a view of another form of air-regulator. Figs. 7 and 8 illustrate other forms of soldering-bits which may be used in place of that shown in Fig. 5.

In the drawings, 1 is the tubular reservoir for containing the liquid fuel. Secured to the forward end of the reservoir 1, as shown, is the front cap 2, provided with the forwardly-projecting tubular member 2'. The cap 2 is provided with an outwardly-projecting flange, so as to form the reservoir 2' for the reception of alcohol, gasolene, or other inflammable material to be used for a purpose hereinafter to be described. Screwed into the forward end of the tubular member 2' is the mixing-chamber 3, having closed rear end 4, as shown. Through this closed end 4 is the fine feeding passage or duct 4'. The space within the tubular member 2' and the closed portion 4 of the mixing-chamber is filled with asbestos, as shown. Adjacent to the rear end of the mixing-chamber 3 I provide the lateral openings 5 for the admission of air, so as to form with the fuel coming

from the feed-port 4' a highly-combustible mixture. The exterior of the mixing-chamber is provided with the flange 7, upon which is screwed the soldering-bit 8. The forward end 3' of the mixing-chamber extends into the interior of the bit, as shown in Fig. 1. Surrounding the tubular member 2' and the mixing-chamber 3 is the air-regulating thimble 6. (Shown in plan, Fig. 4.) This regulator is made of perforated sheet metal having lateral openings 6', which register with the openings 5 of the mixing-chamber. At the forward end of this regulator I provide the notch 6', which in connection with the stud 3', projecting laterally from the mixing-chamber, forms a suitable stop for limiting the rotary movement of the regulator 6.

The bit, as illustrated in Figs. 1 and 5, is hollow and provided with numerous perforations 8' to form outlets for the products of combustion. The hollow bit thus formed provides a combustion-chamber, and I find in operation that I am able to heat the bit to the requisite degree in much less time than is possible with any similar structure with which I am acquainted.

At the rear of the cap 2 I provide the projection 9, having the lateral elbow portion 9'. Passing longitudinally through the projection 9 I provide the duct 10, and laterally through the same, as shown, I provide the duct 11. The outer ends of these ducts 10 and 11 are closed by the small screw-closures 11'. In the axial center of the reservoir 1 I provide the feeding-tube 12, which is supported by means of the elbow 9', through which it passes. The opening 11 communicates directly to the interior of such tube 12. This tube is a trifle shorter than the reservoir 1, as shown, so as to permit the play of the valves 14 at either end thereof, the ends being provided with the valve-seats 15 to form a liquid-tight valve. The stems 13 of the valves 14 project within the tube 12 and form suitable guides or retaining devices for the valves 14. Between the adjacent ends of the valve-stems 13 and within the tube 12 I place the sliding weight 16.

The rear end of the tubular reservoir 1 is closed by the cap 17, which has the funnel-shaped mouth 18 and the screw-plug 20, screwed into the end of the cap 17, as shown. The screw-plug 20 is provided with a handle 19 for convenience in turning the screw-plug 20. In this manner I am able to provide suitable means for replenishing the supply of

fuel when the same shall have become exhausted.

In the use of the device I find it necessary to regulate the supply of fuel, and to do this I provide the needle-valve 25 for regulating the size of the passage 10. This valve 25 is carried by the stem 21, which in turn has the handle 22, the stem 21 being screw-threaded at 26 into the metal 2² of the cap, as shown. 10 I also provide the gland 23, surrounding the valve-stem 21, for the purpose of preventing leakage. It will be noted that the valve-stem 21 projects angularly into the cap 2. This is for the purpose of making use of the 15 handle 22 of the valve-stem as a foot upon which the whole device may be supported with the heated bit elevated, as illustrated in Fig. 1.

In Fig. 6 I have shown a modified form of 20 air-regulator, in which the openings 6³ are triangular in form. I find that under some conditions this form of opening gives better results, for the reason that the influx of air through a slight opening will direct a current 25 close to the duct 4'. I may also dispense with the perforations 6² and make the regulator of plain sheet metal. (Not shown.) I find, however, that the perforations will permit a sufficient supply of air to mix with a 30 minimum supply of fuel to keep the bit 8 at a sufficient temperature for ordinary work, while the openings 5 are covered by the otherwise solid portion of the regulator. When a larger supply of fuel is admitted to the 35 burner, then a larger supply of air is required, under which conditions the openings 6' or 6³ may be made to register with the openings 5 of the combustion-chamber 3. Thus I am enabled to properly regulate both 40 fuel and air supply.

In the use of my soldering-iron the reservoir is filled by unscrewing the plug 19 20, using the funnel-shaped opening 18 for such purpose. When the reservoir 1 is filled with 45 fuel, the plug 19 20 is restored, and the device is held in a vertical position, and gasoline, alcohol, or other inflammable material is poured in the cup or reservoir 2³ and lighted. The heat generated by the burning of this 50 fuel will gasify a portion of the gasoline and create a pressure within the reservoir 1, which pressure will force the fuel through the tube 13, passages 11 and 10 to saturate the asbestos within the chamber 2', and finally 55 through the duct 4', where it will ordinarily be lighted by the flame from the burning fuel in the cup 2³. Otherwise it may be lighted by a burning match.

When the gas has begun to form within 60 the reservoir, due to the heating of the cup 2 and adjacent parts, the generation of gas is continuous so long as there is any flame from the duct or nozzle 4', for the reason that gasoline being normally volatile the heat transmitted by the metallic parts from the duct

or nozzle 4' will be sufficient to maintain a constant pressure within the reservoir 1, which pressure being upon the surface of the liquid will force the same through the tube 13 and the passage 11 10, and this no matter 70 which end of the reservoir may be up. It will be readily seen that if the soldering-iron be inverted, so that the cap 17 shall be uppermost, the valve 14 at the left-hand end of the reservoir, as illustrated in Fig. 1, will fall 75 to the seat 15, while the sliding weight 16 will fall against the end of stem 13 of the other valve, and thus unseat the valve adjacent to the head 2. It will thus be seen 80 that no matter which end of the reservoir is uppermost a passage-way for liquid fuel is always formed below the surface of such fuel, while the opening above the surface is always closed. Again, when the head 8 is uppermost the heated parts are nearest the surface of the liquid, thus giving a much more rapid generation of gas, and therefore an increased pressure upon the surface of the liquid fuel. With the handle 19 uppermost, the gravity-feed will be found sufficient. 85

I wish it to be understood that I do not desire to be limited to the exact details of construction shown and described, for obvious modifications will occur to a person skilled in the art. 90

I claim—

1. In a gasoline soldering-iron, the combination of a tubular reservoir, a cap at each end of said reservoir, a gasifying-chamber and a mixing-chamber, a valved passage leading from the reservoir to the gasifying-chamber, an absorbent non-combustible material filling said latter chamber and a gas-passage from the latter chamber to the mixing-chamber, air-passages leading into said mixing-chamber and means to regulate the supply of fuel to said gasifying-chamber and a thimble having triangular apertures therein, said thimble being rotatably mounted upon said mixing-chamber for regulating the air-supply to said mixing-chamber. 105

2. In a soldering-iron, the combination of a fuel-reservoir, a gasifying-chamber and a mixing-chamber, a valved passage leading from the reservoir to the gasifying-chamber, means for regulating the supply of fuel to the gasifying-chamber, an absorbent non-combustible material filling said latter chamber, a jet or nozzle leading from said gasifying-chamber to the mixing-chamber, apertures in the mixing-chamber adjacent to said jet or nozzle, and a thimble rotatably mounted upon said mixing-chamber, said thimble having triangular apertures therein for regulating the air-supply to said chamber. 115

3. In a gasoline soldering-iron, the combination of a tubular fuel-reservoir, a gasifying-chamber and a mixing-chamber, a fuel-supply tube secured within said fuel-reservoir and located substantially in the center 120

thereof, a passage connecting the interior of said tube with said gasifying-chamber, check-valves seated in the ends of said tube, a sliding weight within said tube adapted to unseat the valves respectively, and a non-combustible absorbent material filling said gasifying-chamber.

4. In a gasolene soldering-iron, the combination of a fuel-reservoir, a fuel-passage leading from said reservoir, a needle-valve in said passage the stem of said valve being inclined to the axis of said passage, a handle upon the valve-stem, said handle having a broad flat surface adapted to serve as a foot for supporting the soldering-iron with one of its ends elevated.

5. A gasolene soldering-iron having a fuel-reservoir, a gasifying-chamber and a combustion-chamber, fuel-passages connecting said chambers, a mass of absorbent non-combustible material filling the gasifying-chamber, a needle-valve intercepting one of said passages, said valve having a handle with a broad flat surface forming a foot for supporting the soldering-iron with the combustion-chamber elevated.

This specification signed and witnessed this 24th day of February, 1906.

HENRY BERG.
